UNITED STATES PATENT OFFICE.

WILLIAM E. HARKNESS, OF MARION, OHIO.

COIN-ASSORTER.

1,212,215.

Specification of Letters Patent. Patented Jan. 16, 1917.

Application filed December 31, 1915. Serial No. 69,690.

To all whom it may concern:

Be it known that I, WILLIAM E. HARKNESS, a citizen of the United States of America, residing at Marion, in the county of Marion and State of Ohio, have invented certain new and useful Improvements in Coin-Assorters, of which the following is a specification.

This invention relates to coin assorters.

10 The primary object of this invention is to provide a mechanism that is adapted to receive and direct the course of travel of a conglomeration of coins of different sizes and denominations and which can be manipulated to force the different sizes or specific denominations to be subjected to a sifting and sliding operation by means of which the different sizes or denominations of the coins are made to travel in specific 15 and well defined courses to the terminal of each course at which point they are deposited or dropped into separate and removable receptacle.

A further object of this invention is to 20 construct the paths of the courses by means of a series of separate and perforated plates, and arranging them in spaced and overlapping relation with respect to each other so that, when the coins in their travel reach 25 the terminals of each plate which are located above and at pre-determined points along the path of the courses, they will be precipitated upon the next succeeding lower plate and by the impact, tumbling and jarring caused by the dropping of the coins 30 thereon, they will be assisted to separate from each other provided, they have adhered to each other prior to being precipitated upon the lower plate.

35 A further object is to provide means of assembling and maintaining the separate plates in the above described relation by fitting them to a series of inclined, progressive kerfs formed in spaced relation to each 40 other, around a pivotally hung supporting member.

45 Another object is to so form the plates that they will counteract the tendency of the coins from being thrown outward and 50 rearward from the center of the paths of the courses, by their centrifugal force, when the mechanism is being operated to perform the sifting and sliding functions in assorting the coins, and means integral with each

plate to positively maintain the overlapping ends of the plates from contact with each other.

55 Another feature of this invention comprises a means of imparting a slight rising and falling vertical movement to the supporting member that has the effect of vibrating or shaking the coins thereby assisting in separating them from each other and giving impetus to them to force them to slide over the paths of the courses more readily 60 and means of abruptly jarring the assorting mechanism.

65 Another feature of this invention is to provide suitable means on the bottom of the coin assorter, to direct each different size of 70 the coins received from a specific course, through a particular aperture or slot formed in the bottom of the coin assorter, whereby the different sizes of coins are dropped or deposited in segregated and removable 75 receptacles.

75 Other features of this invention consist in the method of receiving and guiding the mixed mass of coins so that they will be deposited in the first instance upon a chute 80 and thence directed to the first plate of the first course of the coins, and the means of pivotally hanging the supporting member upon a vertical rod which is made to pass up through the central portion of the supporting member to engage a cone bearing 85 attached to the top of the supporting member.

These and other objects are attained by 90 the mechanism illustrated in the accompanying drawings in which:

Figure 1, is a side elevation of the invention, showing a portion of the casing broken away to show the terminals of several courses, and it also shows removable 95 receptacles attached to the bottom of the pivotally hung supporting member in position to receive coins from said courses. Fig. 2, is a side elevation of the invention with part of the casing removed showing the arrangement of the inclined kerfs which are formed in the supporting member, the means of imparting an oscillating rotary, 100 vibrating and jarring movement to the mechanism, and one series of plates in their overlapping progressive and spaced relation 105 which forms one course for the travel of a specific denomination or size of a coin, also

showing the upper portion of a chute. Fig. 3, shows a side elevation of a fragment of the supporting member having one or the first plate of six different courses mounted in the inclined kerfs formed on one side of the supporting member spaced apart from each other, overlapping and co-operating in progressive relation with other plates to form a part of a series of courses with another series of plates arranged in the same manner around the supporting member but at right angles to each other. Fig. 4, is a fragmentary side view of the supporting member taken at right angles to Fig. 3 showing the inclined relation of the chute with respect to the first plate and several succeeding plates arranged around the supporting member in progressive relation to each other. Fig. 5, is a top plan view of the invention showing the supporting member, a chute, and a series of plates mounted in the inclined kerfs and arranged in co-operative spaced and overlapping relation to form a specific course for coins of one size, around the supporting member. Fig. 6, is an inverted plan view of the bottom plate of the supporting member which is attached thereto and provided with a series of slots, a holding and supporting means for the removable receptacles, and an operating lever for the assorting mechanism. Fig. 7, is a sectional view taken on the line $\alpha-\alpha$ of Fig. 6.

In the drawings, reference numeral 1 represents a base, 2 a vertical boss having a central aperture 3 formed therein into which a vertical rod 4 is fitted and secured. The rod 4 is provided with a tapered end 5. A supporting member 6 has a block 7 secured to the top thereof and is provided with a tapered bearing 8 which is located directly over an aperture formed through the central portion of the supporting member to receive the vertical rod 4. The tapered end 5 of the rod is journaled in the tapered bearing 8 of the block 7 thereby providing means of pivotally hanging the supporting member upon the end of the vertical rod. A plurality of series of inclined kerfs 9 are formed in or arranged around the vertical exterior of the supporting member in spaced, overlapping and progressive relation from each other. A plurality of series of plates 10 are fitted to the kerfs 9 thereby forming a plurality of courses around the supporting member. The plates forming the first five courses are preferably perforated and the plates of the sixth course imperforate. The plates are all arranged around the supporting member as follows to wit: the first is the dollar course, the second the half-dollar course, the third the quarter course, the fourth the nickel course, the fifth the penny course and the sixth the dime course. This arrangement is shown in Fig. 3 the first

plate of each course being numbered respectively 11-12-13-14-15 and 16.

A chute 17 is secured to the block 7 at an incline to the supporting member and its mouth extends above and is alined with the first plate 11 of the first course. A bottom plate 18 which conforms and coincides with the exterior outlines of the plates forming the various courses is secured to the bottom of the supporting member, and it is provided with a series or plurality of vertical slots 19 which are arranged at pre-determined points around the supporting member. A casing 20 is fitted around the exterior of the bottom plate and a sound deadening lining 21 is interposed therebetween. A top 22 having a funnel 23 is provided for the casing and the mouth of the funnel is located directly over the top of the chute 17. The above described arrangement of the casing, top and bottom plate entirely incloses the plates forming the several courses, and the supporting member. Each one of the courses is made to terminate at predetermined points around the supporting member before the paths thereof reach the bottom plate which leaves a gap between the terminals of the courses and their respective slots in the bottom plate and said gaps are bridged to form a continuous path, to the slots by the imperforate plates 24 which have their ends 25 down-turned and fastened to the bottom plate adjacent to one side of the slots. Stop or guiding plates 26 are fastened to the bottom adjacent to the opposite sides of the slots thereby forming vertical guide passageways in line with the vertical slots and contiguous with the path of the courses.

An operating lever 27 is fastened to the bottom plate 1 of the supporting member and is provided with an eye 28 which loosely fits the vertical rod 4. Members 29 which are provided with enlarged heads 30 are secured to the bottom plate on each side and in front of the slots and a spring catch 31 is arranged at the opposite ends of the slots as shown in Fig. 6. Receptacles 32 are provided with rectangular open wire frames 33, and these are attached to the mouth of the receptacles. The frames are adapted to slidably engage and be supported upon the enlarged heads 30 of the members 29, the rear portions of the wire frames being forced to yieldingly engage the spring 34 catches thereby yieldingly locking the receptacles in their normal positions which is directly underneath the slots. A portion of the top face of the boss 2 is cut away at 35 leaving the equivalent of a gear tooth 36. The gear tooth is adapted to contact with a downwardly depending tapered pin 37 which is attached to the operating lever 27 riding thereover and thereby imparting a slight rising and falling vertical movement 38.

to the supporting member and the mechanism carried thereby, when an oscillating rotary movement is imparted to said mechanism, by the manipulation of the operating lever 27. To maintain the overlapping ends of the plates positively in spaced relation from each other to prevent possible wedging of the coins between the plates, spacing members 37 are provided, upon which the preceding plate rests. The spacing members are preferably made integral with the underlying plates. A portion of each side of the plates adjacent to one end is provided with a flange 38 to prevent the coins from being thrown off the plates by their centrifugal force, when an oscillating rotary movement is imparted to the assorting mechanism by manipulation of the operating lever 27. In order to limit the oscillating rotary movement of the assorting mechanism while it is being transported, a chain 39 is attached to the boss 1 and the end 40 of the operating lever. The ends 41 of the plates are curved to direct the travel of the coins inwardly toward the supporting member as they slide therefrom and are precipitated upon the next succeeding plate.

Attention is called to the fact that the number of courses formed by plates can be increased or decreased by changing the height of the supporting member. The number of plates used can be varied and their form changed, or other immaterial changes made in the structure and arrangement of the parts without departing from the spirit of the present invention.

Attention is called to the fact that the present application and drawings shows and describes a coin assorter that is designed to assort six different sizes or denominations of coins which is the preferred type, but it is obvious that the number of different sizes of coins to be assorted can be varied by a slight change in the structure.

The operation of the coin assorting mechanism is as follows: The travel of only one size coin or denomination will be described as the travel along the paths of the various courses of the different denominations or sizes of coins in the sliding, sifting and separating operation are identically the same and the functions performed by the assorting mechanism in separating the different coins are also identical. Referring now to Fig. 2 the operator pours a mixed mass of coins in the funnel 23 and they drop upon the chute 17 sliding therefrom by gravity upon the first plate of the first course 11 which course retains the coins of largest size or dollar denomination. A large number of the small sized coins drop down immediately through the perforations of the next succeeding plates until they reach a plate of a specific course that has perforations that are not large enough to permit

specific sizes of coins to drop through. When the coins are deposited on the plates which have perforations of less size than said coins, the coins then start to slide by gravity over all the inclined plates forming the perforated path of their specific course. The operator of the coin assorting mechanism then grasps the operating lever 27 and imparts an oscillating rotary movement thereto which in turn partially rotates the supporting member and the coin assorting mechanism carried thereby. As the handle is moved back and forth the pin 36 contacts with the gear tooth 35 and the pin travels up and over said gear tooth imparting a slight rising and falling movement to the supporting member which carries the coin assorting mechanism. The extent of the oscillating movement of the operating lever 27 is regulated by the walls A and B of the cut away portion which provides stops to contact with the pin 36, and the pin also provides means of jarring or vibrating the assorting mechanism at the end of each stroke of the operating lever. The slight rising and falling vertical movement imparted to the supporting member and its mechanism vibrates and jars the mechanism thereby assisting in separating the coins if perchance any of them should adhere to each other and accelerates the sliding movement of the coins along the perforated paths of the courses in a separate relation from each other. When the operator imparts an oscillating rotary movement to the operating lever 27 the coins are forced to slide by gravity along the perforated paths of the courses around the supporting member and when the coins in their travel reach the end of each plate forming the paths of the courses they drop or tumble by gravity from the curved end 41 upon the next succeeding plate of the course and the impact thereon assists in separating them from each other and giving impetus to the travel during the sifting and separating operations. It will be observed that the ends of each plate are in spaced relation from the next succeeding plate thereby interrupting the continuity of the perforated paths of the various courses, and when specific sizes of coins reach the terminals of their courses they are deposited upon the guiding means or path which bridges the gap between the ends of the terminals and the vertical slots, said slots being arranged in direct communication with the mouths of the removable receptacles which are adapted to receive pre-determined specific sizes or denominations of coins. As the coins travel around their specific courses and reach the curved ends 41 of the plates they are carried inwardly by the curved ends toward the supporting member thereby counteracting the centrifugal force of the coins when the coin assorter 130

ing mechanism is being operated, and the flanges 38 prevent the coins from being thrown off the plates (forming the courses) by the centrifugal force thereof, when the 5 coin assorting mechanism is being operated as described above. In manipulating the lever 27 to impart an oscillating rotary movement to the coin assorting mechanism a slight jerking movement is preferable. 10 As the coins travel around their various courses they are prevented from being wedged between the overlapping ends of the plates because of the spacing members 37 which positively hold them spaced apart 15 from each other at all times and under all circumstances. When the operator is imparting movement to the coin assorting mechanism the coins continue to slide over the perforated paths continuously until they 20 reach by the sifting operation their particular course from which point they continue to slide by gravity and the movement imparted to them by the operator of the assorting mechanism until they reach the terminals of their specific courses and from 25 which point they are conducted by the bridging and guiding means or path to a pre-determined point where they are deposited into their specific removable and segregated receptacles. When the different 30 sizes of coins are sifted, assorted and guided in their travel to their specific removable receptacles the operator grasps the handle C and withdraws a specific removable receptacle from its supporting means, empties the receptacle of its contents and then replaces it to receive another charge of coins from its specific course. The terminals and bridging means can be arranged at 35 any point most convenient in the construction of the assorting mechanism.

What I claim is:

1. In a coin assorter, a supporting member having a plurality of series of inclined kerfs arranged around the exterior surface thereof in angular progressive relation with respect to each other, a plurality of series of perforated plates fitted to said kerfs in overlapping relation to each other forming separate courses, means made integral with the plates to prevent the overlapping portions from contacting with each other, and a single series of imperforate plates also forming a course around the supporting member. 45
2. In a coin assorter, a supporting member having a plurality of series of inclined kerfs arranged around the exterior surface thereof in angular progressive relation with respect to each other, a plurality of series of perforated plates fitted to said kerfs in overlapping relation with each other forming separate courses, means made integral with the plates to prevent the overlapping portions from contacting with each other, a single series of imperforate plates also forming 50
3. In a coin assorter, a supporting member having a plurality of series of inclined kerfs arranged around the exterior surface thereof in angular and progressive relation with respect to each other, a plurality of series of perforated plates fitted to said kerfs in overlapping relation to each other forming separate courses, means made integral with the plates to prevent the overlapping portions from contacting with each other, a single series of imperforate plates also forming a course around the supporting member, an inclosing casing for said plates, and means to impart an oscillating rotary movement to the supporting member and the mechanism carried thereby. 55

70

75

3. In a coin assorter, a supporting member having a plurality of series of inclined kerfs arranged around the exterior surface thereof in angular and progressive relation with respect to each other, a plurality of series of perforated plates fitted to said kerfs in overlapping relation to each other forming separate courses, means made integral with the plates to prevent the overlapping portions from contacting with each other, a single series of imperforate plates also forming a course around the supporting member, an inclosing casing for said plates, a bottom secured to the casing which is provided with a series of slots, guiding means forming a continuity of the paths of the courses from the terminals thereof to the slots in the bottom of the casing. 80

85

4. In a coin assorter, a supporting member having a plurality of series of inclined kerfs arranged around the exterior surface thereof in angular and progressive relation with respect to each other, a plurality of perforated plates fitted to said kerfs in overlapping relation to each other forming separate courses, means made integral with the plates to prevent the overlapping portions from contacting with each other, a single series of imperforate plates also forming a course around the supporting member, an inclosing casing for said plates, a bottom secured to the casing which is provided with a series of slots, guiding means forming a continuity of the paths of the courses from the terminals thereof to the slots in the bottom of the casing, and separate receptacles removably attached in alignment with and underneath said slots. 90

95

5. In a coin assorter, a pivotally hung supporting member provided with a plurality of series of inclined kerfs arranged and secured in spaced, angular and progressive relation with respect to each other around the exterior of the supporting member, a plurality of series of perforated plates fitted to said kerfs to overlap each other and form a plurality of separate courses the continuity of the paths thereof being interrupted because of the spaced relation of the plates with respect to each other. 100

105

6. In a coin assorter, a pivotally hung supporting member, in combination with a series of perforated plates having one of their sides upturned adjacent to one end and their opposite ends curved; said plates being arranged at an incline, in spaced and overlapping relation around the supporting member to form a course and means integral with the plates to maintain their overlapping portions spaced apart rigidly and posi- 110

tively from each other, and means to impart a vibrating or jarring movement to the mechanism.

7. In a coin assorter, a casing, means of supporting the casing to permit vertical and gyratory movement, a series of plates arranged around said supporting means forming separate inclined courses, each plate of said series being spaced apart with respect

10 to the other and a hopper arranged to feed coins to the initial plate of the first course.

8. In a coin assorter, a casing, means for supporting the casing to permit vertical and rotary movement thereof, and a series of plates arranged in similar parallel courses, the plates of each course being progressively inclined from the horizontal, throughout the length of the course and following a circular path throughout the course, the plates 20 of each course being arranged in superimposed relation vertically of the casing and formed respectively with openings of different sizes, the plates of each course presenting a series of lapped sections vertically spaced at their lapped terminals and means carried by the lower section to engage and support the upper section.

9. A coin assorter including a base, a casing supported for movement on the base, a plurality of spirally arranged separated and spaced apart plates disposed within the casing, each forming an independent coin course, a plurality of receptacles removably carried by the casing above the base, and means for directing the coin from each course into a particular receptacle, and means to feed the coins to the initial course.

10. A coin assorter including a casing, a plurality of spirally disposed plate sections arranged within the casing and forming independent coin courses, a base, means carried by the base for rotatably engaging the casing above the uppermost plates, an operating member carried by the casing, and a projection depending therefrom, the base 40 being formed with spaced recesses to alternately and successively receive the projection whereby the casing may be rotated and simultaneously reciprocated.

In testimony whereof I affix my signature. 50

WILLIAM E. HARKNESS.
